UNITED STATES PATENT OFFICE.

WILLIAM D. BALLERSTEDT, OF LOS ANGELES, CALIFORNIA.

ROTARY STEAM ENGINE.

Application filed May 20, 1924. Serial No 714,555.

This invention relates to cut off steam engines of the rotary type.

An object of this invention is to provide a rotary engine operable by expansive fluid, and adapted to isolate charges of such fluid between the inlet and outlet ports, and to use the expansion of such isolated fluid to revolve the rotor of such motor.

Another object is to avoid any application 10 to the rotor of back pressure from the expansive fluid.

An object is to provide a rotary engine in which the energy of an isolated charge of expansive medium is utilized to drive the motor 15 independently of the source of supply throughout a considerable portion of a revolution of the rotor after the expansive charge has been cut off from the supply.

The invention is broadly new, basic and 20 pioneer in various features among which are the following:

In this invention a rotor in a cylinder is provided with a swinging piston the heel of 25 which is pivoted to the rotor and fitted to the circular cylinder wall, and the swinging end of which piston is connected to a link that is arranged to swing on a center that is eccentric to the rotor; the parts being so arranged that movement of the free end of the piston, operates through the resolution of forces, to advance the rotor.

Another pioneer feature resides in the combination with a cylinder having a circular wall, a peripheral intake, and a lateral outlet; of a rotor provided with a peripheral abutment, and having a working fit with the walls of the cylinder; pistons, each adapted to swing on an axis eccentric to the rotor, and forming a working fit at its heel with the abutment, and with the circular wall of the cylinder, and adapted on its outer face to conform to the circular wall of the cylinder with a working fit when the piston is fully swung outward, and to conform to the forward side of the abutment when the piston is fully swung inward; and a link, the inner end of which is arranged to revolve about an axis eccentric to the cylinder chamber; the heel of said swinging piston being pivoted to the rotor and constructed, adapted and arranged to cooperate with the abutment and with the wall of the cylinder to isolate charges of the expansive medium in rapid succession.

An object is to provide a rotary engine adapted to long life and ready repair, and to

this end I provide case hardened bearings for the heels of the pistons, which are practically nonsubject to wear and which are constructed in combination with the other parts, so that 60 they can be easily and quickly replaced in case of wear.

Another object is to so construct a rotary engine that the rotor can work freely without loss of expansive medium.

Another object is simplicity in construction and operation.

Features of invention are shown in the construction, combination and arrangement of parts whereby a compact engine of great 70 power is produced.

Another object is to make provision for utilizing the pressure of the expansive medium to balance the rotor.

A broad and pioneer feature of the invention lies in rotor carrying pistons and fixed abutments; and means whereby the impelling fluid at first acts at the periphery to drive the abutments forward and rotate the rotor and to move the piston inward with like result; and means whereby in regular course the impelling fluid is transferred from the peripheral side of the abutments, respectively, to the inner side of the abutments.

Another feature resides in a rotor having 85 peripheral abutments, and swinging pistons arranged between circular walls arranged to fit a cylinder and provided with ports and passages or ways to admit expansive medium from the peripheries of the walls to the space 90 between the walls; said walls having lateral ports for exhaust of expanded medium from opposite sides of the rotor and the cylinder having exhaust ports, ways or passages oppositely arranged to allow exhaust of the expanded medium intermittently as the ports of the piston pass the exhaust outlets.

Other objects, advantages and features of invention may appear from the accompanying drawings, the subjoined detail description and the appended claims.

The accompanying drawings illustrate the invention in the form at present preferred, with four pistons, to the swinging ends of which the characters *a*, *b*, *c* and *d* are applied 105 in the order in which steam has been applied successively.

Figure 1 is an end elevation of a steam engine constructed in accordance with this invention, a portion of one cylinder head 110 being broken away to show a part of the exhaust port; broken lines indicate the shaft

and the anti-friction bearing therefor and also the eccentric pin.

Fig. 2 is an elevation of the intake and exhaust side of the engine looking at the right side of Fig. 1.

Fig. 3 is an end elevation omitting the cylinder head shown in Fig. 1. The transfer channel and the final exhaust passage at the further side of the engine are indicated 10 in broken lines.

Fig. 4 is a view of the cylinder and working parts in position when steam is first admitted, to an abutment to drive the motor, and to the piston *d*, following such abutment, 15 to swing the piston inwardly to revolve the rotor, while an isolated expansive charge operates against the preceding piston *c* to swing it inwardly to rotate the rotor; the next preceding piston *b* receiving steam between 20 its inside face and its abutment and the steam behind the next preceding piston *a* being open to the exhaust. The anti-friction bearings are omitted from this view.

Fig. 4^a is a view showing the cylinder in 25 section on line $x^{4a}-x^8$, Figs. 2, 9 and 10, and showing the pistons, the abutments and links in outline; portions being broken away to expose parts otherwise hidden; and broken lines indicating other features not exposed 30 in this view. The rotor is shown with the piston at *d* in steam taking position and near the cut off position before the close of its inward expansion stroke; the piston at *c* is shown at the end of its inward stroke, the 35 piston at *b* is shown at the beginning of its exhaust stroke and the piston at *a* between exhaust and intake positions.

Fig. 5 is a broken sectional view on line 40 x^5 , Fig. 4^a showing the inlet port.

Fig. 6 is a fragmental detail in section on line x^6 , Fig. 4^a, showing the exhaust outlet and one of the balancing valves; arrows indicate the exhaust flow.

Fig. 7 is a fragmental detail partly in section on line x^7 , Fig. 6, showing the exhaust passage and the direction of flow of the exhaust.

Fig. 8 is a section on line $x^{4a}-x^8$, Figs. 2, 45 9, and 10, showing the different positions of the pistons and the operation of the cut offs. The large arrow indicates the direction of rotation. Broken lines are employed to show parts otherwise hidden.

The piston at *a* in this view is well along on 55 its inward stroke, the piston at *d* has finished its inward stroke; the piston at *c* is started on its outward swing with an equalization of pressure on its inner and outer sides; and the piston at *b* is exhausting.

Fig. 9 is a section on line x^9 , Fig. 8.

Fig. 10 is a section on line $x^{10}-x^{10}$, Fig. 8.

Fig. 11 is a view of one of the case hardened knuckle bushes.

Fig. 12 is a quarter turn view of the knuckle bush shown in Fig. 11.

Fig. 13 is a transverse section of the knuckle bush on line x^{13} , Fig. 12.

Fig. 14 is a longitudinal section on line x^{14} , Fig. 15 of one of the swinging pistons.

Fig. 15 is a view of the inner face of the 70 swinging piston shown in Fig. 14.

Fig. 16 is a central longitudinal section of one of the stationary abutments detached.

Fig. 17 is a section on line x^{17} , Fig. 16, looking toward the outer end of its abutment. 75

Fig. 18 is an edge view of a link for connecting the swinging end of one of the pistons to the eccentric pin.

Fig. 19 is a side view of the link shown in 80 Fig. 18.

Fig. 20 is an edge view of a link for connecting the swinging end of a second piston to the eccentric pin.

Fig. 21 is a side view of the link shown in 85 Fig. 20.

Fig. 22 is an edge view of a link for connecting the swinging end of a third piston to the eccentric pin.

Fig. 23 is a side view of the link shown in 90 Fig. 22.

Fig. 24 is an edge view of a link for connecting the swinging end of a fourth piston to the eccentric pin.

Fig. 25 is a side view of the link shown in 95 Fig. 24.

Fig. 26 is an enlarged fragmental plan partly in section on line x^{26} , Figs. 7 and 27, with parts broken away to show interior construction and exhaust outlet and one of the rotor balancing exhaust valves.

Fig. 27 is an enlarged fragmental elevation partly in section on line x^7-x^{27} , Fig. 6, of the exhaust chamber and valve showing a fragment of the rotator and exhaust pipe.

The cylinder 1 may be of any desired diameter and length and suitably mounted as by the base 2; said cylinder is provided with circular chamber 3 and has peripheral inlet 4 at one side of said chamber and an expansive medium transferring way 5 open to the circular chamber 3 and extending partly around the inside peripheral circular wall 6 of the cylinder chamber 3 on the side opposite the inlet 4. A rotor 7 is arranged to revolve inside the chamber and comprises circular end walls 8, 8'' which are spaced apart and fitted to the circular wall 6 of the cylinder and are adapted to rotate in said cylinder on an axis 9 central thereto and provided with oblique abutments 10 fixed to and revolving with the rotor and conforming at the outer ends to the circular chamber. A shaft 11 is connected to said rotor and extends centrally from one end wall of the rotor through one head of the cylinder. Pistons 12 are pivoted at their heels by pivots 13 to the rotor, adjacent the outer ends of the abutments respectively and have swinging ends 13' that are movable toward and from the circular cylinder wall; and said pistons are adapted on 125 130 135

- their outer sides to conform to said circular wall, and are arranged to be swung inwardly from said wall responsive to expansive pressure between the wall and the pistons, and
- 5 are connected to revolve about an axis 15 eccentric to the cylinder chamber so that when the abutments 10 are revolved around the axis of the cylinder, the swinging ends 13' of the pistons will yield to pressure between said
- 10 pistons respectively and the circular wall of the chamber. Eccentric axis 15 is so arranged relative to the axis 9 of rotor 7, and to the peripheral inlet 4, that the links 14 will operate as moving struts to cause the swinging
- 15 ends 13' of the pistons to approach the peripheral wall 6 of the cylinder as said ends approach the peripheral inlet 4, and so that when a piston is acted upon by an expansive medium admitted to the cylinder through the
- 20 inlet 4, the inward movement of the swinging end of the piston yielding to the pressure of such medium, will be accommodated by a circular movement of the rotor; and the pressure upon the piston 12 will be translated by
- 25 resolution of forces through the links 14 to the rotor to cause it to revolve and to advance the abutment from the inlet, so as to open an outlet from the expansion chamber 16 to the transfer way 5.
- 30 Said transfer way 5 is wider than the space between the end walls 8, 8" of the rotor, and said end walls are provided with passages 17 leading from the peripheries of the end walls of the rotor to communicate with
- 35 the passage 18 in the respective abutment. For convenience of construction the abutments are shown as made independently of the rotor end walls, and are fixed to said end walls by suitable means as the bolts 19.
- 40 The peripheral wall 20 and the rear wall 21 of each abutment are closed to the steam admitted at the intake 4 to the space or pocket 16 between the swinging pistons and the peripheral wall 6 of the chamber, so that
- 45 when the steam or other expansive medium enters at 4, it will act upon the rear face of the abutment, and between the peripheral wall and the swinging piston; and will swing the piston inward while the impact of the
- 50 steam on the abutment will be effective in conjunction with the pressure upon the swinging piston, to rotate the rotor; and the expansion of the medium continues to force the swinging end of the piston inward after the knuckle preceding the outer end of the abutment has passed the inlet 4, as indicated in Fig. 4.
- The space between the end of the inlet 4 and the beginning of the transfer passage 5 is
- 55 greater than the distance between the heel 13' of the swinging piston 12 and the rear face 21 of the abutment with which the swinging end 13' of said piston cooperates to form a pocket for retaining the steam between the piston, the circular wall and the rearward
- face of the abutment; and the inner face of the swinging piston and the outer face of its companion abutment, are conformed to each other so that owing to the eccentricity of the axis on which the links 14 swing, the revolving rotor brings the lateral port 18 of the abutment into position to open the ports 17 to the lateral extensions 16' of the transfer passage 5. The pistons are arranged as shown in Fig. 8 to close the outlet 18' from the passage 18 as by means of a valve portion 23 of the swinging piston; and as the rotor revolves the port 18 is opened as indicated at 24 in Fig. 8.
- Said piston 12 is provided with an intermediate passage 25 adapted to transfer the expansive medium from outside the piston to the space 26 between the outer side of the abutment 10 and the inner face of the swinging piston 12. This occurs at the time when the moving strut thrusting link, as at 14' is beginning to move the piston toward the periphery; and at a time when the piston, as at 17' is beginning to start toward the curved wall 6 of the chamber; and the steam thus admitted into the space between the abutment and the swinging piston equalizes the pressure on the outer and inner faces of the piston and expands between the inner face of the swinging piston, and the outer face of the abutment.
- The rotor is provided with a number of exhaust ports 27 that extend through the side walls of the rotor and are so positioned that as the rotor revolves to a position where the steam in the inner expansion chamber 26, is entirely expanded, and the outer surface of the piston is fitted against the wall of the cylinder, the exhaust port 27 of the rotor will open to an exhaust passage 28, leading through a head of the cylinder to the exhaust pipe 29.
- When the rotor walls are in a position so that the passage 18 is opened to the lateral extension 16' of the transfer passage 5, the inner end of the passage 18 is closed by the forward end 23 of the piston.
- As each piston approaches and passes the exhaust port 28 in the cylinder wall, the port 27 in the wall of the rotor registers with said port 28 and said ports 27 and 28, and the links 14 and eccentric 30 are so arranged in conjunction with each other, that as the rotor revolves in the position shown in Fig. 4^a, the exhaust is completed from the inner face of one piston and said piston remains extended outward to fit the circular wall of the cylinder, and the steam from intake 4, pressing upon the preceding piston which is at the bottom of the view in Fig. 4^a, begins to swing the piston in, and the operation hereinbefore described is repeated.
- It is understood that any suitable form of bearing eccentric to the axis 9 may be employed, and in the drawing the eccentric is

shown as a pin 30 having an enlarged threaded head 31 to screw into a boss 32 in one head 33 of the cylinder. Said threaded head 31 is provided with a wrench seat 34 by which the 5 pin may be screwed into and out of place. The head 33 has an inwardly projecting trunnion 35 concentric to the axis 9 of the rotor, and said trunnion is provided with a bore 36 that is within the periphery of the trunnion 10 and is eccentric to said trunnion and to the axis of rotation 9.

37 indicates the bush in the bore 36, and the pin 30 fits the bush 37 tightly so that the pin 30 is rigidly held eccentric to the axis of rotation 15 of the rotor. Said pin extends across the space between the rotor wall 8 and 8".

The rotor wall 8" is provided with a roller bearing seat 38, and the anti-friction bearing 39, is seated in said seat and is carried 20 by the trunnion 35 which carries the rotor head 8".

The links 14 are supported on a roller bearing 40 carried by the eccentric pin 30. The head of said eccentric pin is protected by a 25 cap 41 which may serve as a chamber to supply grease to the grease duct 42 in the eccentric pin to supply grease to the roller bearing 40.

The shaft 11 is shown as constructed integral with the wall 8 of the rotor; and the head 43 of the cylinder is provided with an 30 internal boss 44 having a ball bearing chamber 45 in which an anti-friction bearing 46 is mounted to support the shaft 11 that extends through the cylinder head 43 and 35 a flange bushing 47, which holds packing 48 in the head.

The rotor wall 8 is shown provided with a 40 cavity 49 which may be supplied with lubricant and which is open to the anti-friction bearing 46.

Wearing plates 50 are let into the inside 45 faces of the cylinder heads 33 and 34, and are shown secured by screws 51.

Each of the links is provided with a bearing 50 52 on which the pistons 12 are swung. Said links 14 are rigid and are constructed as indicated in Figs. 18-25 to practically close the space between the eccentric bearing 55 and the piston. The outer ends of the links 14 are pivoted to the swinging ends of the 50 pistons by pivots 52.

The cylinder heads 33 and 43 have corresponding exhaust passages 28 and each passage 55 28 has an enlargement 53 to accommodate the balancing valve 54 of a balancing screw 55 that is threaded through the cylinder head 43. There are two of said balancing valves arranged diametrically opposite to each other in the cylinder heads 33 and 43, and are adapted to choke or open the exhaust from the opposite ends of the rotor to cause the flow of steam through the 60 rotor to be equally discharged from opposite 65 sides thereof.

The joints at the pivoted ends of the pistons are protected by bushes 56 having cylindrical ends 57 (see Figs. 11, 12 and 13) with pintle holes 58 therethrough and a semi-cylindrical web 59 at each end. These 70 knuckles may easily be made of case hardened tool steel and afford protection against wear.

The knuckle in combination with the circular wall 6 are adapted to form steam cut 75 offs to isolate the partially expanded steam so that the pressure can be applied to the swinging ends of the pistons as hereinbefore explained.

In the drawings the pipe 4' is indicated 80 as an ordinary pipe; but the intake is shown as flattened to deliver the pressure entirely across the space between the end walls of the rotor.

It is understood that the shape of the abutments, the pistons, the intake 4, and other 85 passages, may be changed within the judgment of the constructor without departing from the spirit of this invention and I do not limit my invention to the exact shapes and 90 forms of passages, ports and parts shown.

It is understood that the invention may be used as a meter and also as a pump for either liquid or expansive fluid.

By reversing the motor it may be operated 95 as a pump. In such case power would be applied to the rotor shaft from an external source of power, not shown in the drawings.

I claim:

1. The combination of a cylinder having a 100 circular chamber, a peripheral inlet at one side of said chamber, and an expansive medium, transferring way extending partly around the inside peripheral wall of the cylinder on the side opposite the inlet; a rotor comprising circular end walls spaced apart and fitting the 105 circular wall of the cylinder, and adapted to rotate in said chamber on an axis central thereto and provided with oblique abutments fixed to and revolving with the rotor and conforming at the outer ends to the circular chamber; a shaft connected to said rotor and extending centrally through one head of the cylinder; pistons pivoted to the rotor adjacent the respective ends of the abutments, and having swinging ends that are movable toward and from the circular cylinder wall, and which are adapted to conform to said wall and to be swung inwardly from said wall responsive to expansive pressure between such wall and the 110 pistons respectively; said transferring way being adapted to conduct the expansive medium from the outside to the inside of said pistons; links connected to the swinging ends of the pistons and to an axis eccentric to said cylinder chamber to which said pistons are revolvably mounted.

2. A circular rotor comprising two walls, and abutments between said walls, the walls and abutments being in fixed relation to each 115 120 125 130

other, the walls being spaced apart by the abutments, and the abutments being spaced apart from each other in circular arrangement around the axis of the rotor; a shaft fixed 5 to the rotor co-axial therewith; a cylinder having a circular chamber in which the rotor is journaled concentrically to revolve; said cylinder having two heads between which the rotor is fitted; cylindrical bearing means 10 connected to and supported by the cylinder and revolubly supporting the rotor in the cylinder; a link supporting bearing eccentric to said rotor supporting bearing; links supported by, and oscillatable relative to the rotor 15 and link supporting bearing; pistons carried by the rotor near the rim thereof and adapted to swing toward and from such rim and the circular wall of the cylinder, the links being pivotally connected to cooperate 20 with the swinging pistons to supply fluid medium from one side to the other of a piston of the swinging pistons during a portion of each rotation of the rotor; and means to allow discharge of fluid from between the 25 swinging pistons and the circular wall of the cylinder during another part of such rotation.

3. In a rotary engine having a cylinder and a rotor; an abutment fixed to the rotor and co-operating with the cylinder wall to form a 30 cut off; said cylinder wall having an inlet and a transfer way; a swinging piston pivoted to the rotor, and cooperating with the rotor, the abutment and the cylinder to form expansion chambers on opposite sides of the piston; and means for transferring expansive medium from one side to the other side of a piston for the purpose of allowing swinging of the piston on its axis as the rotor revolves.

40 4. The combination with a cylinder having a circular chamber with peripheral and lateral passages for an expansible fluid; of a rotor having end walls spaced apart and abutments and pistons cooperating therewith arranged between such walls; the walls of said cylinder and rotor being provided with peripheral and other passages adapted to allow fluid to flow through the rotor between the peripheral and lateral passages of the cylinder 45 to conduct the fluid from one side to the other side of said pistons, for the purpose of exhausting the expanding medium.

5. The combination with a rotor carrying swinging pistons and fixed abutments, of 55 means whereby an impelling medium is caused to first act at the periphery of the rotor to drive the abutments forward and rotate the rotor and to move the pistons inward with like result; and means whereby in regular 60 course the impelling fluid is transferred from the outer sides of the abutments and pistons respectively, to the inner sides of the pistons for the purpose of exhausting the impelling medium.

66 6. The combination with a rotor carrying

swinging pistons and fixed abutments, of means whereby an impelling medium is caused to first act at the periphery of the rotor to drive the abutments forward and rotate the rotor and to move the pistons inward with like 70 result; means whereby in regular course the impelling fluid is transferred from the peripheral sides of the abutments, respectively to the inner side of the abutments; and means for exhausting the impelling medium. 75

7. In a motor having a rotor carrying abutments fixed to the rotor, and swinging pistons arranged to cooperate with the rotor and the abutments; and means adapted to apply the movement of the swinging pistons to rotate 80 the rotor; of ways through the periphery of the rotor, through the abutments and the pistons to apply impelling medium between the outer faces of the abutments and the inner faces of the pistons the swinging ends of 85 said pistons being linked to an axis eccentric to the axis of the rotor; and exhaust means to allow the expanded impelling fluid to escape from the motor.

8. In a motor having a cylindrical chamber, a rotor mounted to revolve in said chamber and provided with abutments and pistons and with peripheral and other ways extending through the rotor walls, the abutments and pistons, respectively, and through the 90 rotor walls to communicate between the spaces between the abutments respectively and their respective pistons to conduct the operating fluid from one side of the pistons to the other, and ways communicating between 95 the outside of the cylinder and the space underneath the abutments and the pistons; and means cooperating with said last named ways for allowing escape of fluid. 100

9. A motor comprising a cylinder having 105 a circular wall; a rotor having end walls spaced apart and fitting the cylinder, said cylinder having an intake and a transfer way, the intake being at one side and the transfer way at an opposite side of the cylinder; said transfer way being of greater width than the space between the rotor walls, and the rotor walls being provided with peripheral ways to communicate with the transfer way, and the rotor being provided with abutments and swinging pistons cooperating therewith, and forming pockets; and ways in said rotor adapted to communicate with the transfer way of the cylinder for the purpose of delivering expansive fluid from pockets outside 110 the swinging pistons to pockets inside the swinging pistons, said transfer way being of greater width than the space between the rotor walls to permit cooperation with said last named ways. 115

10. A motor of the character set forth, having a rotor provided with circular walls spaced apart, and provided with abutments and pistons between the walls; and a cylinder in which the rotor is mounted and is 120

adapted to be revolved, and which cylinder is provided with an intake to admit expansive medium to the pistons to drive the rotor, and with outlet means to allow exhaust of expanded medium, said cylinder having a transfer way of greater width than the space between the inner faces of the rotor walls, and said rotor walls having ways to conduct expansive medium from the space between the 10 rotor walls toward the exhaust outlet.

11. A motor of the character set forth having a rotor provided with spaced apart circular walls and having abutments and pistons; and a cylinder in which the rotor revolves said cylinder provided with means to allow exhaust of expanded impelling medium from the rotor; said rotor having abutments and adapted to be impelled by an expansive medium applied against the pistons and abutments at the periphery of the motor; said cylinder having an intake for impelling medium, and a transferred way of greater width than the space between the inner faces of the rotor walls, and being spaced from the intake 25 and adapted to allow expanded impelling medium to pass onward toward the exhaust when the pistons, respectively have ended the inward stroke.

12. A rotary engine having inside a cylinder; a rotor having side walls provided with ways, and also having between said ways, abutments and pistons which are provided with passages, ports and ways for expansive medium; said pistons being arranged in com-

bination with other ports, to swing responsive to pressure of expansive medium, and also adapted to open and close the passages, ports and ways to flow of the expansive medium as the rotor revolves and means to apply the expansive medium to the rotor.

13. In a motor having a cylinder and a rotor in the cylinder; the combination of an abutment fixed to the rotor; and a piston pivoted to the rotor and cooperating with the cylinder and abutment to form a pocket; said abutment having a lateral inlet and a port; and said piston having a passage communicating with an outlet from the rotor; of means operable as the rotor revolves, to move the piston into positions successively for admitting practically expanded medium between the abutment and the piston to open an outlet for such medium to exhaust when the piston is in its outermost position.

14. The combination with a cylinder and a rotor therein adapted to be driven by expansive medium; said cylinder being provided with ports on opposite sides of the rotor for discharge of expanded medium from opposite sides of the rotor; means at opposite sides of the cylinder to adjust the discharge of medium from the rotor for the purpose of balancing the rotor.

In witness whereof, I have hereunto set my hand at Los Angeles, California, this 12th day of May, 1924.

WILLIAM D. BALLERSTEDT.
